CLAIM

The ornamental design for a board-mount connector, as shown and described.

DESCRIPTION

FIG. 1 is a top perspective view of a board-mount connector showing our new design;

FIG. 2 is a front elevation view thereof;

FIG. 3 is a back elevation view thereof;

FIG. 4 is a side elevation view thereof;

FIG. 5 is a top elevation view thereof;

FIG. 6 is a bottom elevation view thereof; and,

FIG. 7 is a bottom perspective view thereof.

The broken line in the figure drawing views is included for the purpose of illustrating unclaimed environment only and forms no part of the claimed design.

1 Claim, 4 Drawing Sheets
